CHARGING TONGS FOR LIFT TRUCKS

Joseph H. Jones, Canton, Ohio, assignor to Republic Steel Corporation, Cleveland, Ohio, a corporation of New Jersey

Application June 9, 1950, Serial No. 167,181

1 Claim. (Cl. 214—115)

1

The present invention relates generally to the material handling art and is more particularly concerned with novel apparatus for transporting articles such as billets and ingots.

In industrial operations, such as loading re-heating furnaces, it is necessary to lift and carry elongated metal billets and to introduce them into the furnaces before and during the firing operations. These billets are far too heavy to be lifted and carried about by hand and the expense of such an operation would prevent its use commercially even if the billets were of substantially reduced size and weight. Accordingly, various means and devices have been developed for the purpose of handling such articles and some of these devices have come into wide general use. To the best of my knowledge, however, none of the devices thus developed prior to this invention have proven to be entirely satisfactory, a common shortcoming being their excessively large number of parts and their high manufacturing cost due to their complexity.

In contrast to the devices of the prior art, the apparatus of this invention consists of relatively few parts which are not expensive to manufacture or assemble. Furthermore, the present apparatus lends itself readily to combination with a standard lift truck including the conventional upright mast and means for moving the mast vertically in the usual manner. Such combination has the further advantage of being substantially more economical than the prior art devices including vehicle means and of being easier to operate and more versatile in operations such as lifting billets from the mill floor, carrying them endwise to the furnaces, thrusting them through the furnace doors and releasing and dropping them within furnaces when they are clear of the furnace side walls and door sills. The ease of operation of the present devices enables the introduction of the billets into the furnace and the release of them therein rapidly so that the operator of the vehicle and the carrying apparatus itself are not subject to too much high temperature heat in the course of the operation.

Those skilled in the art will gain a further understanding of this invention and further objects and advantages thereof upon consideration of the following detailed description of apparatus embodying the invention in a preferred form, reference being had to the drawings accompanying and forming a part of this specification, in which:

Fig. 1 is a perspective view of a conventional lift truck equipped with the said preferred apparatus of this invention;

2

Fig. 2 is a side elevational view of a portion of the apparatus of Fig. 1 including the head piece, tong means extending forwardly of the head piece and mechanism for opening and closing the tongs;

Fig. 3 is an end elevational view of the apparatus of Fig. 2 taken on line 3—3 thereof;

Fig. 4 is a sectional view of valve means to control the operation of the tong operating mechanism;

Fig. 5 is a sectional view in plan of the free end of the apparatus of Fig. 1 showing the tongs and the operative connection between the tongs and operating mechanism therefor, and;

Fig. 6 is a fragmentary, elevational, sectional view of the lower portion of the frame of the Fig. 1 apparatus, showing how the frame is mounted for tilting motion in a vertical arc.

As illustrated in the foregoing drawings, the apparatus of this invention comprises generally an upright frame, a head associated with the frame and movable vertically therein, and gripping and holding means carried and supported adjustably by the head for supporting articles to be carried by the apparatus. This gripping means in general includes a pair of tongs and actuating mechanism associated with the tongs for opening and closing them.

The combination apparatus of this invention involves the foregoing structure and a conventional lift truck having a mast and means for moving the mast and the head together vertically in the frame.

More in detail, the apparatus of the foregoing drawings comprises a conventional lift truck T including an upright telescoping frame F, a telescoping mast M disposed in the frame and associated therewith and connected to a slide member 10 of the frame, a head H secured to member 10 and slidable therewith in the frame, and means including power transmission apparatus for operating the mast. This transmission apparatus includes a sprocket S secured to slide member 10 by a bracket B and a driving chain

C for applying lifting force through bracket B and head H to the mast and member 10. In addition, the truck is equipped with a pair of cylinders Y (one being illustrated) which are connected to approximately the mid-section of frame F and are stationarily mounted on the truck to move the frame through a vertical arc from about 15 degrees forward of the vertical position to about 15 degrees rearwardly thereof around a pivot near the bottom of the frame.

55 The pivot attachment of the frame to the truck

is made in the conventional manner by means of brackets 12 (Fig. 6).

Head H comprises a generally rectangular, fabricated, metal body, the portion of which facing forwardly of the frame comprises a metal plate 13. Plate 13 is provided with a plurality of spaced apertures (not shown) arranged in a circular pattern to receive bolt means 14 for fastening firmly to the head the tong assembly and operating apparatus therefor. Plate 13 also has a central aperture 16, the purpose of which will be described, and is welded around its periphery to a frame 18, which together with plate 13 constitutes said head.

Tong means G and operating mechanism O therefor are supported by an elongated, generally cylindrical housing 20 having flanged ends 21 and 22, the latter one of which is attached by bolt means 14 to the head H. Housing 20 is provided between its ends with an elongated, axially extending access opening 24 to facilitate repair and maintenance of the tong actuating mechanism. Flange 21 is of reduced diameter compared to flange 22 but like flange 22 is provided with a plurality of spaced apertures (also not shown) arranged in circular pattern around the housing to receive bolt means 27.

Mechanism O comprises a hydraulic cylinder 28 as shown in Fig. 4 having a clevis 29 at its ends adjacent to head H for attachment by means of a bolt 31 to a retaining bar 33 connected to head H by a bolt 34 extending through aperture 16 and a nut 35 screwed onto bolt 34 and bearing on the inner surface of plate 13. Cylinder 28 is provided with the usual fluid inlet and outlet ports 38 and 39, respectively, on opposite sides of a piston 40 which is reciprocated in the cylinder under fluid pressure differentials across the piston established in the usual manner. A piston rod 42 is screwed into a threaded axial aperture of piston 40 and extends forwardly of the piston through a packing gland 43 and terminates in a threaded portion 45 disposed outside cylinder 28.

Tong means G comprises a pair of tongs 50 composed of mated tong links 51 opposed to and spaced apart from each other at their pivot points. Links 51 are pivoted on a pair of pins 53 secured to the forward portion of a bell-shaped tong head 55. The tongs are operatively associated with mechanism O by means of a yoke 57 connected to a rod 58 which reciprocates with piston 40 relative to head 55, being connected by means of a coupling 59 to end 45 of rod 42. Yoke 57 has a transverse aperture 60 in which opposed adjacent end portions 61 of links 51 are received and retained for motion relative to each other as the tongs are opened and closed.

In the operation of the present device, the driver of the truck maneuvers it into position adjacent to an end of the ingot I and then raises or lowers the head H and tongs 50 to bring the tongs into position to grip the end portion of the ingot, tilting frame F as necessary to pick up the ingot. The tongs then are closed on ingot I by causing piston 40 to move to the position shown in Fig. 4, and the truck is driven to a point adjacent to the furnace so that the ingot extends into the furnace. The piston is then moved to its forward position so that the tongs are opened, as shown in Fig. 5, and the ingot is dropped in the furnace clear of the furnace sills and side walls.

Having thus described the present invention so that those skilled in the art will be able to get a better understanding and practice the same, I state that what I desire to secure by Letters Patent is defined in what is claimed.

What is claimed is:

In a lift truck having a mast and means for vertically moving the mast, the combination of a substantially vertically disposed elongated frame pivotally secured near its lower end to the truck for tilting motion relative to said truck, a head associated with the mast and movable up and down therewith in said frame, a hollow open-ended generally cylindrical housing secured at one end to the head and extending therefrom forwardly of the truck and having an axially extending access opening, and gripping and holding means carried and supported adjustably by the truck for supporting articles to be transported, said gripping means comprising a cylinder disposed in and supported by said housing and secured to the head and extending forwardly of the said truck, a piston rod in the said housing and extending forwardly from the cylinder, and tong means disposed adjacent to the free end of the cylindrical housing and carried by said piston rod for gripping articles to be transported by the truck.
